UNITED STATES PATENT OFFICE.

EDWARD H. ELDER, OF CHICOPEE FALLS, MASSACHUSETTS, ASSIGNOR
TO THE J. STEVENS ARMS & TOOL COMPANY, OF CHICOPEE FALLS,
MASSACHUSETTS, A CORPORATION.

EJECTOR MECHANISM.

No. 824,535.

Specification of Letters Patent.

Patented June 26, 1906.

Application filed March 16, 1905. Serial No. 250,360.

To all whom it may concern:

Be it known that I, EDWARD H. ELDER, a citizen of the United States of America, residing at Chicopee Falls, in the county of 5 Hampden and State of Massachusetts, have invented new and useful Improvements in Ejector Mechanism, of which the following is a specification.

This invention relates to firearms, and has 10 special reference to improvements in the ejector mechanism for the breakdown type of a firearm, the object of the invention being to provide an improved ejector and barrel-stop, the specific construction and advantages of which will be fully described in 15 the following specification and pointed out clearly in the claim appended thereto, reference being had to the accompanying drawings, in which—

20 Figure 1 is a sectional elevation of the frame and breech end of a gun-barrel to which the construction embodying the invention has been applied, the barrel being in tipped-down position. Fig. 2 is a similar 25 view showing a slight modification of the construction shown in Fig. 1. Fig. 3 is a transverse section on line 3 3, Fig. 1, showing the relation of one of the ejector-actuating parts to the frame and to the ejector 30 mechanism. Fig. 4 is a perspective view of the under side of a part of the barrel and lug, showing the position of the forward end of the latch-lever relative to the forward end of the lug.

35 The construction forming the subject-matter of this application is in the nature of an improvement on my prior Letters Patent of the United States, dated December 11, 1900, and numbered 663,604 and involves a 40 change in the construction shown in said patent to provide a strong barrel-stop and the addition to said construction of an element for actuating the ejector mechanism and constituting besides an additional barrel- 45 stop.

Referring to the drawings, *a* indicates the frame of the gun, and *b* the barrel, on the under side of which is the usual barrel-lug *c*, the barrel being pivotally supported in the forward end of the frame on the pin *d*. The lug 50 has a hole bored therethrough lengthwise

close to the under side of the barrel to receive the ejector-stem *e*, provided with the usual head *f* to engage the rim of a cartridge *g*. The ejector-stem has a sliding movement in 55 its seat and is provided with a notch *h* on its under side with which the upturned end *j* of a latch-lever *k* engages when the stem is pushed toward the pin *d* to bring the head *f* into a position flush with the end of the barrel. The lug *c* is vertically slotted, as at *m*, to receive the end *j* of the latch-lever, and said lug on the under side thereof is longitudinally slotted, as at *o*, to receive the body of the latch-lever, as shown in my said prior 60 patent.

The forward end of the latch-lever has a circular recess *p* extending transversely across the end thereof to fit the pin *d*; but the latch is pivoted on the pin *q*, extending 70 through it and the lug and located, as shown, a little below the pin *d* back of the latter and parallel with it, this end of the latch-lever having a vertically-disposed portion *r* extending across the forward open end of the 75 hole in which the ejector-stem *e* is located. This stem does not extend entirely through the lug lengthwise, and there is a spiral spring between its inner end and the vertical end *r* of the latch-lever, which spring is normally under compression to a sufficient degree to effect the actuation of the ejector when the latch-lever is operated by the tipping-down movement of the barrel and disengaged from the notch *h* in the stem of the 80 ejector, the fixed abutment against which the spring *e'* acts being the vertical forward end *r* of the latch-lever. The lower part of the forward end of this lever is extended beneath the pin *d* to a point beyond it, as shown at *s*, 90 which is so located as to come to a bearing against the frame beneath it when the barrel is tipped down, whereby the opposite end of the latch-lever will be disengaged from the extractor-stem, and when this tipping-down 95 movement is carried far enough to cause this forwardly-extending tongue *s* to come to a bearing against the under side of the pin *d* while its extremity bears downwardly on the frame, it constitutes a stop for the barrel. 100

At the rearward end of the latch-lever a T-shaped lever *t* is pivoted, as at *v*, the rec-

tangentially-extending head *w* of which is adapted to engage with shoulders *x*, formed in the sides of the frame by chambering the latter, as shown in the cross-sectional view, 5 Fig. 3. This lever *t* hangs down loosely below the latch-lever, being let into a recess in the latter, as shown, whereby it is prevented from swinging quite to vertical position to the end that when the breech of the gun is 10 closed it will strike the bottom of the frame and be swung to a position of parallelism with the lower edge of the lug and into a recess *y* in the latter. This lever *t* may be so proportioned that it will disengage the latch-lever 15 and act as a barrel-stop by the engagement of its head *w* with the shoulder *x*, and it may be arranged to operate in conjunction with the forwardly-extending tongue *s* to perform both of the functions, or it may be so arranged that it will disengage the latch-lever 20 alone and then in conjunction with the tongue *s* act as a barrel-stop.

The usual stop pin or screw *z* is located in the barrel-lug to enter a recess in the under side of the stem *e* of the ejector to limit the movement of the latter endwise.

Instead of using the swinging lever *t* a transversely-disposed pin 3 may be located in the rear end of the latch-lever *k* about in the position shown in Fig. 2, which may extend beyond the sides of the barrel-lug to engage the shoulders *x* in the sides of the frame, said shoulders in that case being located higher up on the frame, as seen in said figure, the barrel-lug being recessed, as at 4, to permit the rear end of the latch-lever to be swung up far enough to engage the notch in the ejector-stem.

Having thus described my invention, what

I claim, and desire to secure by Letters Patent of the United States, is—

In a firearm of the character described, a barrel pivotally supported in the forward end of the frame, an ejector, a lug *c* on the lower side of the barrel, a longitudinal slot therein, 45 a latch-lever *k* pivoted in the said lug and slightly below and in rear of the pivot supporting the barrel, a longitudinal hole extending through said lug close to the under side of the barrel, an ejector-stem *e* located 50 in the hole in the lug, said pivoted latch-lever having an upturned part *r* extending across the forward end of the longitudinal hole in the lug, a compression-spring *e'* located between the end of the upturned part of the 55 ejector-lever and the end of the ejector-stem, the ejector-stem having a sliding movement in its seat, a part *s* integral with the latch-lever and extending forward and below the pivot for the barrel and adapted to engage 60 the forward end of the frame when the barrel is tilted, a notch in the under side of said ejector-stem and normally engaged by the forward end of the latch-lever, a depending T-shaped lever *t* pivoted to the rear end of the 65 latch-lever and occupying a chambered portion of the frame, shoulders above said T-shaped lever whereby when the barrel is tipped downward the forwardly-extended part of the latch-lever engages the frame, 70 and the latch-lever is released from the ejector-stem allowing the same to be moved by the compression-spring, and the said shoulders are engaged by said T-shaped lever.

EDWARD H. ELDER.
